UNITED STATES PATENT OFFICE

RUDOLPH J. WARNER, OF BUFFALO, NEW YORK, ASSIGNOR TO WARNER JEWELRY
CASE COMPANY, OF BUFFALO, NEW YORK, A CORPORATION OF NEW YORK

JEWELRY BOX

Application filed June 24, 1927. Serial No. 201,107.

This invention relates generally to jewelry boxes, but more particularly to a box for displaying a lady's ribbon-watch.

One of its objects is the production of a neat and attractive box of this kind having a multi-color pad which may be made of sections of various shapes or designs.

Another object of the invention is to simplify the construction of the pad with a view 10 of reducing the production cost of the box.

In the accompanying drawings:—

Figure 1 is a perspective view of a jewelry box embodying the invention. Figure 2 is a sectional end view, showing the movable 15 pad-section in a standing position. Figure 3 is a perspective view of the removable pad-section. Figure 4 is a central cross section of the box-body on an enlarged scale.

Similar characters of reference indicate 20 corresponding parts throughout the several views.

10 indicates the body of the box and 11 its cover, which parts may be provided with a covering of velvet or other suitable material.

25 Arranged in the box-body is a pad, which, in its preferred form, comprises a number of panels or sections 12, 13, 14 of contrasting shades or colors closely fitted together at their adjoining edges and of the proper 30 shape and dimensions to completely fill the box, as shown. Each panel may consist of a strip or core 15 of cardboard or other stiff material having a decorative covering 16 of velvet or other appropriate material.

35 One of the panels, say the rear one 12, may be permanently secured in the box, while the other two may be removably arranged in the box and secured to a packing or bottom board 17 having a folding brace 18, so

40 that this double panel-section may be placed in an inclined position in the box, like an easel, to better display a lady's wrist watch or piece of jewelry mounted upon it, as shown in Fig. 2. If it is desired to display

45 the watch in a horizontal position, the brace is folded and the removable panel is laid in the box flush with the fixed panel, as shown in Fig. 1. The bottom board is preferably co-extensive with the middle and front 50 panels. The removable double panel sec-

tion may be provided, as shown in Figure 1, with a suitable tab to facilitate its removal from the boxes.

To render the display attractive, the central panel 13 of the pad may, for instance, 55 be black and the front and rear panels 12 and 14 green, or vice versa. Various other color-combinations or shades may be adopted according to the fancy of the manufacturer or the customer.

60 The panels may also have a variety of outlines; for example, in the box shown in Figs. 1 and 2, the central panel tapers from its middle toward its ends and the side panels taper in the opposite direction.

The box-body may have the customary neck or collar 19, but the adjoining edges of the pad preferably abut directly against each other without an intervening neck or other part, as shown in the drawing.

70 In a box having a three-panel pad with one fixed and the other two removable, the panels are preferably covered as best shown in Fig. 4. As there illustrated, the coverings of the central and front panels are folded over the opposing edges of their cores 15, while the other edges of these coverings are folded down over the opposite edges of the panel-cores 15 and around the corresponding front and rear edges of the bottom board 75 17, as well as the ends of these members, the lower edges of the coverings being glued or otherwise secured to the underside of the board 17. A finishing strip or sheet 20, which carries the brace 18, is applied to the 80 back of this double panel.

85 A material saving of time is effected by this manner of covering the pad-panels and the bottom-board.

The core of the rear panel, which has no 90 bottom board, is made thick enough to bring the surface of said panel flush with that of the other panels.

95 By employing the fixed pad-section 12 in association with the movable or easel-section 13, 14, the configuration of the latter may be varied to produce a variety of pleasing designs, the fixed section following the outline of the easel-section and being complementary thereto so that the two sections com- 100

CERTIFICATE OF CORRECTION.

Patent No. 1,769,247.

Granted July 1, 1930, to

RUDOLPH J. WARNER.

It is hereby certified that error appears in the printed specification of the above numbered patent requiring correction as follows: Page 2, lines 29 to 31, claim 3, strike out the words "disposed in the same plane with their exposed surfaces substantially flush with each other" and insert the same to follow after the word "panels" in line 27; and that the said Letters Patent should be read with this correction therein that the same may conform to the record of the case in the Patent Office.

Signed and sealed this 9th day of September, A. D. 1930.
